Des. 179,618
Patented Jan. 29, 1957

179,618

COMBINED SAIL, MOTOR, AND ROW BOAT

Johannes H. Wendt, Williams Bay, Wis.

Application May 19, 1955, Serial No. 36,126

Term of patent 14 years

(Cl. D71—1)

FIG. 1

FIG. 2

FIG. 3

Fig. 1 is a top plan view of a combined sail, motor, and row boat embodying my new design with the sail omitted and the mast broken away;

Fig. 2 is a fragmentary front elevational view; and

Fig. 3 is a side elevational view thereof with the sail in position.

I claim:

The ornamental design for a combined sail, motor, and row boat as shown.
